UNITED STATES PATENT OFFICE.

NICOLAUS AUGUST OTTO, OF COLOGNE, ASSIGNOR TO THE GAS-MOTOREN-FABRIK DEUTZ, OF KÖLN-DEUTZ, GERMANY.

APPARATUS FOR GOVERNING GAS OR PETROLEUM MOTOR ENGINES.

SPECIFICATION forming part of Letters Patent No. 433,808, dated August 5, 1890.

Application filed April 10, 1890. Serial No. 347,348. (No model.) Patented in England March 17, 1890, No. 4,164; in Belgium March 22, 1890, No. 89,920, and in Italy April 19, 1890, LIII, 264.

To all whom it may concern:

Be it known that I, NICOLAUS AUGUST OTTO, a citizen of Prussia, residing at Cologne, in the German Empire, have invented new and useful Improvements in Apparatus for Governing Gas or Petroleum Motor Engines, (for which I have obtained Letters Patent in Belgium, dated March 22, 1890, No. 89,920; in Italy, dated April 19, 1890, Vol. LIII, No. 264, and in Great Britain by an application for patent, which patent when granted will bear date March 17, 1890, No. 4,164,) of which the following is a specification.

This invention relates to that construction of gas or petroleum motor engines in which the admission of the combustible gas or liquid into the cylinder is effected by means of a valve controlled by an inertia governor with "hit-and-miss" device—that is to say, in which, when the engine runs too fast, a reciprocating rod acted upon by a weight, and which ordinarily pushes against a notch or projection on the gas-valve lever so as to open the gas-valve, is moved by the inertia of the weight so as to miss the valve-lever, and thus cause the valve to remain closed.

According to my present invention I combine with the gas-valve or valve-lever a catch or stop which acts upon the discharge-valve of the engine or upon the gear thereof in such a manner as to hold the discharge-valve open during the time when the gas or oil admission valve is not acted upon by the reciprocating rod, so that during the ensuing strokes of the piston the products of combustion, together with air, are alternately expelled and drawn into the cylinder again, instead of only drawing in and expelling air, whereby the unnecessary cooling down of the cylinder during the time that the engine is running without power is prevented.

Figures 1 and 2 of the accompanying drawings shew, by way of example, a gas-motor engine of vertical construction with the above-described invention applied thereto.

b is the gas-valve, the rod of which is connected by a bell-crank lever *w* to a sliding rod *k*, opposite which is a rod *a*, pivoted to a slide *p*, and having a weighted arm *p'* fixed

to it, the slide *p* having a to-and-fro motion 50 imparted to it by a link *o*, connected to the rod *q*, that works the gas-slide *r* of the engine. *n* is the discharge-valve of the engine, closed by a spring and opened during the discharge period by means of a bell-crank lever *e e'*, the 55 arm *e* of which bears with a roller *g* against a cam *f* on the counter-shaft that works the gas-slide. The bell-crank lever has a tail with a projecting stud *h*, and a lever *d*, pivoted to the engine-frame, has a hooked end *l*, which 60 catches over the stud *h* when the bell-crank lever *e e'* has been moved into the position shown in Fig. 2 by the cam *f*, in which it holds the discharge-valve open, the lever *d* being acted upon by a spring *m*, which tends 65 to hold it in this position. The other end of the lever *d* is connected by a rod *c* to the rod of the valve *b*, so that when the valve is forced open by the action of the parts *a k w* the lever *d* is at the same time moved so as to 70 release the stud *h*, whereupon the discharge-valve *n* will be closed by its spring.

From the above description it will be seen that every time the discharge-valve is opened by the cam *f* it will be held open by the catch 75 *l* until this is withdrawn again on the opening of the gas-valve *b*, so that when this fails to be opened by the hit-and-miss device *a k* of the inertia governor on the normal speed of the engine being exceeded, as shown at Fig. 80 2, the discharge-valve remains open, allowing the products of combustion to be drawn back again into the cylinder from the discharge pipe or passage, as before described, until, by the reduction of the speed, the inertia gov- 85 ernor again causes the gas-valve to be opened during the charging-stroke, whereupon the discharge-valve will close again.

Having thus described the nature of my invention and the best means I know of carrying 90 the same into practical effect, I claim—

1. In a gas or petroleum motor engine where-
in the discharge-valve for the products of
combustion is kept open during the time that
the normal speed is exceeded, a catch or lock-
ing device operating on the discharge-valve
gear for holding the discharge-valve in the
open position every time it is opened, said

catch or locking device being connected to the gas-valve gear operated by an inertia governor with hit-and-miss device, so that when the gas-valve is opened by said inertia governor 5 the catch or locking device is made to release the discharge-valve.

2. In a gas or petroleum motor engine where-
in the supply of combustible gas or liquid to
the cylinder is effected by a valve controlled
10 by means of an inertia governor with hit-and-
miss device, the combination, with the gas or
petroleum admission valve, of a catch or lock-
ing device acting on the discharge-valve gear
of the cylinder, said catch or locking device
15 being made to hold the discharge-valve open
when the hit-and-miss device fails to open the
gas or petroleum valve, substantially as and
for the purposes described.

3. In regulating apparatus for gas or petro-
leum motor engines wherein the supply of
20 combustible gas or liquid to the cylinder is

effected by a valve controlled by means of an
inertia governor with hit-and-miss device, the
combination, with a bell-crank lever actuated
by the inertia governor and connected to the 25
gas-valve, of a pivoted lever, one end of which
has a catch and which is urged by a spring to
engage with a stud on a lever connected to
the discharge-valve and actuated by a revolv-
ing cam, so that when the discharge-valve is 30
opened it is kept open by the said catch until
it is released by the opening of the gas-valve,
substantially as and for the purposes de-
scribed.

In testimony whereof I have signed my 35
name to this specification, in the presence of
two subscribing witnesses, this 26th day of
March, A. D. 1890.

NICOLAUS AUGUST OTTO.
